(57) **CLAIM**

The ornamental designs for a wetting device, as shown.

DESCRIPTION

The patent or application file contains at least one drawing executed in color. Copies of this patent or patent application publication with color drawing(s) will be provided by the Office upon request and payment of the necessary fee.

FIG. 1 is a perspective view of the wetting device of the present invention;

FIG. 2 is a top view thereof;

FIG. 3 is a front view thereof;

FIG. 4 is a back view thereof;

FIG. 5 is a right view thereof;

FIG. 6 is left view thereof; and

FIG. 7 is a bottom view of the wetting device of the present invention;

FIG. 8 is a top view of the wetting device of the present invention with the transfer plate removed;

FIG. 9 is a front view thereof;

FIG. 10 is a bottom view thereof;

FIG. 11 is a right view thereof;

FIG. 12 is a left view thereof;

FIG. 13 is a back view thereof; and;

FIG. 14 is a perspective view thereof;

FIG. 15 is a bottom view of the transfer plate of the wetting device;

FIG. 16 is a top view of the transfer plate;

FIG. 17 is another view of the transfer plate;

FIG. 18 is another view of the transfer plate;

FIG. 19 is another view of the transfer plate;

FIG. 20 is another view of the transfer plate; and,

FIG. 21 is another view of the transfer plate of the wetting device.
